COMBINED VALVE AND AERATOR
FOR FAUCETS

Sel N. Koblick, 41 Susan Drive,
New City, N.Y. 10956

Filed Oct. 21, 1970, Ser. No. 25,583

Term of patent 14 years

Int. Cl. D23—01

U.S. Cl. D23—20

FIG. 1 is a side elevational view of a combined valve and aerator for faucets, embodying my new design;

FIG. 2 is an end elevational view thereof;

FIG. 3 is a top plan view thereof; and

FIG. 4 is a bottom plan view thereof.

I claim:

The ornamental design for a combined valve and aerator for faucets, as shown.
